US00D631723S

(12) **United States Design Patent**
DeBaker

(10) **Patent No.:** **US D631,723 S**
(45) **Date of Patent:** **** Feb. 1, 2011**

(54) **INSERT BIT**

(75) Inventor: **Joseph Michael DeBaker**, Sussex, WI
(US)

(73) Assignee: **Milwaukee Electric Tool Corporation**,
Brookfield, WI (US)

(**) Term: **14 Years**

(21) Appl. No.: **29/363,247**

(22) Filed: **Jun. 7, 2010**

Related U.S. Application Data

(62) Division of application No. 29/327,520, filed on Nov.
7, 2008, now Pat. No. Des. 623,036.

(51) **LOC (9) Cl.** **08-04**

(52) **U.S. Cl.** **D8/86**

(58) **Field of Classification Search** **D8/82-87;**
81/177.2, 177.85, 442-443, 448

See application file for complete search history.

(57) **CLAIM**

I claim the ornamental design for an insert bit, as shown and
described.

DESCRIPTION

FIG. 1 is a front perspective view of an insert bit of the present
invention.

FIG. 2 is a right side view of the insert bit of FIG. 1, with the
left side view being identical to the right side view.

FIG. 3 is a top view of the insert bit of FIG. 1, with the bottom
view being identical to the top view.

FIG. 4 is a front view of the insert bit of FIG. 1; and,

FIG. 5 is a rear view of the insert bit of FIG. 1.
